OPTICAL ILLUSION WALKING GAME
Kenneth E. Parks, Montgomery, Ala.
(1424 Querida Drive, Colorado Springs, Colo.)
Filed Mar. 26, 1962, Ser. No. 182,334
2 Claims. (Cl. 273—1)

This invention relates to an optical illusion walking game. It has for its main objects to provide such a game that will be highly satisfactory for the purpose intended, requiring simple parts for its operation, and having rules easy to understand.

The game is carried on by the player walking along lines or trails shown on pictures on rugs, mats or the like placed upon a floor and being of sufficient size for the player to look at same through the wrong end of a low powered telescope, binocular or any substitute therefor that will cause an optical illusion such as double eye glasses.

Other objects and advantages will appear from the drawings and specification.

By referring generally to the drawings it will be observed that:

FIG. 1 is a plan view of a trail picture upon a mat, and also showing part of a building at one end.

FIG. 2 is a plan view of a low powered telescope with a hood structure attached.

FIG. 3 is a side elevational view of the telescope.

FIG. 4 is a plan view of a picture upon a mat showing a straight line of numbered blocks, and curved lines of numbered blocks or spaces, and V-shaped lines with numbered spaces.

FIG. 5 is a plan view of a binocular.

FIG. 6 is a side elevational view of binocular.

Similar reference numerals refer to similar parts throughout the several views.

Referring to the drawings in detail it will be seen that the parts for playing the game comprise a piece of cloth 1 or the like or plastic formed as a rug approximately four by ten feet in size having a picture thereon showing a curved trail 2 and part of a building 3; and another similar rug 4 having a picture thereon showing a straight path 5 divided into eight equal-in-length distances; and having a V-shaped path 6 divided into sixteen equal-in-length distances; and a curved path 7 having twenty-four equal-in-length distances. For use by players of the game a low powered telescope 8 is used, or a binocular field glass 9. A hood 10 is mounted on the telescope, and a hood 11 is mounted on the binocular to prevent players from looking at the rugs other than through the telescope or the binocular.

From the foregoing it will appear that a player of the game will be the winner if he or she by skill walks

2

farther along the marked distances on the two rugs, as the game is based upon the fact that it is extremely difficult for a person to walk along a line or course while looking at it through the wrong end of a low powered telescope or binocular. Looking at one's feet and attempting to walk along the line while putting one foot directly in front of the other is similar to walking along a tightrope. The illusion of great height makes it exceptionally difficult to maintain one's balance resulting in a great deal of twisting and other body movement to avoid getting off of the path.

The various parts for playing the game may be made of any material suitable for the purpose. Also the parts may be made in different sizes and capacities.

While I have shown and described the preferred embodiment of my invention, I do not wish to limit same to the exact and precise details of structure, and I reserve the right to make all modifications and changes so long as they remain within the scope of the invention and the following claims.

Having described my invention I claim:

1. An optical illusion walking game comprising, two comparatively oblong shaped mats made of fabric material, one of said mats having an integral picture thereon showing a curved trail and the top portion of a building, the other mat having an integral picture thereon showing a straight path divided into a plurality of equal distances, and also having a V-shaped path divided into a plurality of equal distances, and also having a curved path divided into a plurality of equal distances; a low powered telescope, a hood, this hood being attached to the telescope, this telescope being adapted for looking through its wrong end at said pictures.

2. An optical illusion walking game comprising two comparatively oblong shaped rugs, one of said rugs having an integral picture thereon showing a curved trail in the earth and the top portion of a building, the other rug having an integral picture thereon showing a straight path divided into a plurality of equal distances, and also having a V-shaped path divided into a plurality of equal distances; a low powered binocular field glass, a hood, this hood being attached to the binocular, this binocular being adapted for looking through its wrong end at said pictures.
